JACOB B. OLCH, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS

WEFT-REPLENISHING LOOM

Application filed January 5, 1929. Serial No. 330,632.

This invention relates to improvements in weft replenishing looms and it is the general object of the invention to provide an improved form of brace which can be interposed between the magazine and a part of the loom capable of assuming several different positions.

In weft replenishing looms the magazine ordinarily derives its main support from a loomside and derives additional support from a connection to the arch. Where a loom is built to weave a single type of fabric, such for instance as gingham, the arch will always remain in the same position with respect to the loomside, so that a one-piece brace may be interposed between the magazine and the arch. There are instances, however, where it is desirable to employ an arch which can assume different positions, as for instance, when it is desired to shift from one type of fabric to another, and it is an important object of my present invention to provide a brace which can be interposed between the magazine and the arch irrespective of the position of the latter, the brace being effective in all positions of the arch to steady the magazine.

In the weaving of gingham only two harnesses are ordinarily necessary and because of this fact the arch can be in a relatively forward position near the magazine. If the same loom is to be used for weaving a more elaborate fabric, however, it may be necessary to employ four or more harness frames, in which case the arches will be moved rearwardly to accommodate the added frames.

It is desirable that the inside plate of the magazine be made as compact as possible. The usual brace ordinarily extends from an arm of the magazine to the arch, but inasmuch as movement of the latter may be a matter of several inches to accommodate harness frames of different numbers it is desirable to construct the brace so that the

magazine arm need not be too large. This may be done in such a way as to provide a coarse or stepped adjustment together with a finer or continuous adjustment provided on the arm of the magazine. In this way the arm can be kept small enough so that it will not interfere with the arch when the latter was in its foremost position.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a vertical section through the forward portion of a loom equipped with a magazine and looking in the direction of my invention, parts of the brace being shown in section for the sake of clearness.

Fig. 2 is a top plan view of the brace and certain parts of the loom taken in the direction of arrow 2, Fig. 1, parts being removed for the sake of clearness, and

Fig. 3 shows a detail top plan view of a modified form of connection between the brace and magazine.

Referring to Fig. 1, I have shown a loom-side 10 having a breast beam 11 on which is mounted a magazine designated generally at 12. The magazine has a rearwardly extending arm 13 which as shown herein is provided preferably with a horizontally extending upwardly facing surface 14.

The loom-side has an upper rail 15 which is provided with a slot 16 through which extend bolts 17. There is mounted on the rail an arch 18 through which the bolts 17 pass. The rail extends substantially horizontally so that the arch may be attached thereto in a plurality of positions at different distances from the breast beam and magazine. It is to be understood that in the case of simple fabrics the arch will be relatively close to the

breast beam, whereas if more harnesses are employed the arch will be moved rearwardly. By referring to Fig. 1 it will be seen that the magazine has a foot 19 which is held to the loomside by means of bolts 20 so that the forward end of the magazine is attached to fixed structure and is held in position irrespective of the position of the arches. This is necessary in order that proper delivery may be made of the full bobbin into an empty shuttle.

The matter thus far described is of common construction and of itself forms no part of my present invention, the magazine being if desired of the form shown in prior Patent No. 1,030,748.

In order to brace the magazine from the arch I provide in the preferred form of the invention, a two-part bracket including an arch supported member 30 held to the arch by a bolt 31. This member is provided with a substantially vertical foot 32 which is held in engagement preferably with the front face 33 of the arch. Said arch member 30 is provided with a horizontally extending arm 34 in which is located a relatively long narrow slot 35. There is extending through said slot a bolt 36 having a head 37 on the lower end thereof with a nut 38 at the upper end where it may be readily reached for adjusting purposes. The under surface of the arm 35 is provided with corrugations 39 which cooperate with similar corrugations 40 on a horizontal arm 41 of a magazine brace member 42.

The member 42 may have an offset foot 43 adapted for engagement with the surface 14 of the arm 13. The foot 43 and arm 13 lie to one side of the arm 34 so as not to interfere with movements of the latter. The arm 41 may if desired be provided with a small slot 44 substantially parallel to the slot 35, although this slot 44 is not necessary. A second short slot 45 is formed in the foot 43, said slot 45 being substantially parallel to the slot 35. There is extending through said slot 45 and into and through the arm 13 a bolt 46 having a nut 47 which clamps the foot 43 against the surface 14. While I have shown two slots in the magazine member of the brace yet one will suffice, namely the slot 45 which receives the bolt 46.

When a relatively large number of harnesses are employed the parts may be in the position shown in Fig. 1, but when it is desired to weave a simpler fabric employing only two harnesses the arch may be moved forwardly, in which case it will be necessary to effect an adjustment of the brace. This may be accomplished by loosening the nuts 38 and 47 and moving the arch forwardly to its correct position. It will be understood of course that the location of the arch will be determined by the harness frames and the arch cannot ordinarily be adjusted

to suit the magazine. After the arch is in its new position the nut 38 may be tightened, this operation being accomplished in all likelihood by a slight shifting of the brace members due to the fact that the corrugations do not permit a continuous adjustment but permit only a stepped adjustment. Any slight motion of the magazine member of the brace produced by the interengagement of the corrugations 39 and 40 will be permitted by the slot 45, so that after the nut 38 is tightened the nut 47 may also be tightened. It is to be understood that the adjustment permitted by the slot 45 will be equal at least to the distance between successive corrugations on either of the arch or magazine members.

It will be understood that inasmuch as the magazine must remain fixed with respect to the lay not shown in order to effect correct transfer of a full bobbin, and inasmuch as the arches are located by the harnesses, it is necessary to effect a connection between these two independently and arbitrarily placed members and this adjustment should be continuous. By moving the brace members with respect to each other a rough or approximate or stepped adjustment can be secured, after which the finer or continuous adjustment can be effected by the slot 45. In this way the brace may act merely as a connection between the magazine and the arch without subjecting either to a strain imposed by the other.

While I have stated that only one of the slots in the magazine member of the brace is necessary, yet by a modified construction, a foot 49 similar to foot 43 may be provided with a hole only sufficiently large to accommodate the bolt 46, and a slot 50 may be formed in an arm 51 as shown in Fig. 3. It is sufficient for the purposes of my present invention to be able to effect an approximate or stepped adjustment between the arch members and then be able to effect a finer continuous adjustment between the clamp members and either the arch or the magazine. As shown herein the fine adjustment is effected at the magazine end of the brace, and it is to facilitate this adjustment that the foot 43 rests upon the horizontal upper surface of the arm 13.

From the foregoing it will be seen that I have provided a very simple means for adjusting the brace between the magazine and the movable arch of a loom. It will further be seen that the brace is so made as to afford an approximate adjustment between the brace members and a finer adjustment between one of the brace members and the magazine. It will be seen more broadly that I have provided arch and magazine elements which are connected together by a brace formed of members having a stepped coarse adjustment, said members being capable when approximately adjusted to their cor-

rect length of having a finer adjustment with one of the elements so that neither the arch or magazine elements will be subjected to strain.

Having thus described my invention it will be apparent that changes and modifications may be made therein by those skilled in the art without departing from the spirit and scope of the invention and I do not wish to be limited to the details herein disclosed, but 10 what I claim is:

1. In a loom, a magazine, an arch movable to a plurality of positions at different distances from the magazine, and a brace interposed between the magazine and the arch, said brace having provision for effecting an approximate coarse adjustment and having also provision for effecting a limited continuous adjustment between the magazine and arch.

2. In a loom, a magazine, an arch movable to a plurality of positions at different distances from the magazine, and a brace interposed between the magazine and the arch, said brace including two members having a stepped coarse adjustment with respect to each other, and one of said members having a limited continuous adjustment with the magazine.

3. In a loom, a magazine, an arch movable to a plurality of positions at different distances from the magazine, and a brace interposed between the magazine and the arch, said brace including two members having co-operating corrugated portions by means of which a stepped adjustment may be effected, and one of said members having a continuous limited adjustment with respect to the magazine.

4. In a loom, a magazine, an arch movable to a plurality of positions at different distances from the magazine, and a brace interposed between the magazine and the arch, said brace including a pair of members having cooperating corrugations to effect a stepped adjustment, and one of said members having a slot therein to effect a limited continuous adjustment between the magazine and the last named member.

5. In a loom, a magazine element located in a fixed position with respect to the loom, an arch element adapted to be secured to the loom at a plurality of positions at different distances from the magazine element, a brace 55 formed of two members, means to effect an approximate stepped adjustment between said members, and means to effect a limited continuous adjustment between one of the members and one of the elements.

6. In a loom, a magazine element located in a fixed position with respect to the loom, an arch element adapted to be secured to the loom at a plurality of positions at different distances from the magazine element, a brace 65 member having a substantially vertical foot

secured to one of the elements, a second brace member having a substantially horizontal foot for the other element, means to effect a stepped adjustment between the members, and means to effect a limited continuous adjustment between the second named member and the element cooperating therewith.

7. In a loom, a magazine occupying a fixed position with respect to the loom, an arch capable of assuming a plurality of positions on the loom at different distances from the magazine, a brace member having a vertical foot secured to the arch, a second brace member having a horizontal foot secured to the magazine, means to hold said members together against relative movement with respect to each other, means to effect a stepped adjustment between the members, and means to effect limited continuous adjustment between the second named member and the magazine.

8. A brace for the magazine of a loom having an arch, said brace including two members which are adapted for stepped adjustment with respect to each other, one of said members being capable of having a limited continuous adjustment with the magazine.

9. A brace for a loom having a magazine element and an arch element, said brace including two members which are capable of stepped adjustment with respect to each other, one of said members being capable of having a limited continuous adjustment with one of the elements.

10. A brace for a loom having a magazine element and an arch element, said brace including two members which are capable of stepped adjustment with respect to each other, there being a slot in one of said members, securing means extending through said slot and the other member to hold said members together, one of said members having a slot parallel to the first slot by means of which a limited continuous adjustment between the brace and one of the elements may be effected.

11. A brace for a loom having a magazine element and an arch element, said brace having a pair of similarly corrugated members which are held together in stepped adjustment, and one of said members having a slot extending transversely of the corrugations to effect limited continuous adjustment between one of the elements and the brace.

12. A brace for a loom having a magazine element and an arch element, said brace including two members each of which is provided with corrugations, the corrugations of one member cooperating with the corrugations of the other member to effect a stepped adjustment between the members, one of said members having a slot therein to effect limited continuous adjustment between one of the elements and the brace.

13. A brace for a loom having a magazine element and an arch element, said brace in-

cluding two members each of which is provided with corrugations, the corrugations of one member cooperating with the corrugations of the other member to effect a stepped adjustment between the members, one of said members having a slot therein to effect limited continuous adjustment between one of the elements and the brace, the extent of continuous adjustment being equal at least to the distance between adjacent corrugations.

16 In testimony whereof I have hereunto affixed my signature.
